UNITED STATES PATENT OFFICE.

THEOPHILUS BROWN, OF MOLINE, ILLINOIS, ASSIGNOR TO DEERE & COMPANY, OF MOLINE, ILLINOIS, A CORPORATION OF ILLINOIS.

ROLLING LANDSIDE.

Application filed December 7, 1921. Serial No. 520,646.

To all whom it may concern:

Be it known that I, THEOPHILUS BROWN, a citizen of the United States, residing at Moline, in the county of Rock Island and 5 State of Illinois, have invented certain new and useful Improvements in Rolling Landsides, of which the following is a specification, reference being had therein to the accompanying drawing.

10 My invention relates to plows and more particularly to the landside part thereof, and has for its object to provide a rolling landside having its component parts assembled as a unit ready to be secured in place 15 on the plow with the certainty of correct alinement.

Referring to the drawings in which similar numerals indicate identical parts—

20 Figure 1 is a landside elevation of a plow embodying my invention.

Figure 2 is a transverse section on the line 2—2 of Figure 1.

25 Figure 3 is a section on the line 3—3 of Figure 1, and Figure 4 is a perspective view 25 of the rolling landside and its mounting taken from the furrowward side.

The plow is composed of three principal units; the beam unit, the body unit and the rolling landside unit.

30 The beam unit comprises the beam 1 and the downwardly extending standard 2 adapted to be secured to the body unit, the standard in the instance illustrated being formed by bending a portion of the beam 35 downwardly.

The body unit comprises the frog 4, the moldboard 5, the share 6 and the short landside 7, all rigidly secured together. The frog 4 is provided with a portion 4^a, which 40 presents a face to which the standard of the beam unit is rigidly secured by suitable bolts. The several parts comprising the body unit are manufactured with exactness so that when assembled they not only fit 45 true with respect to each other, but the face of the frog portion 4^a, to which the beam standard attaches, will always be in a plane the exact position of which is predetermined relative to the points that determine the 50 base line of the plow body. Distortions of the beam that may occur during its fabrication due to heating, bending, etc., are corrected so that the beam will occupy its proper position relative to the body unit by 55 heating the standard portion 2 and hammer-

ing and fitting it to the predetermined position given the portion 4^a of the frog; or such correction can well be accomplished by facing the standard, as indicated at 3, by a grinding operation so that the beam standard will have a surface corresponding in position to the predetermined position given the face of the portion 4^a of the frog.

60 The rolling landside unit comprises the bracket 8, the bearing member 9 and the circular landside 10. The bracket 8 is adapted to be secured to the plow body and extends rearwardly, substantially parallel with the short landside 7, and its rear portion is secured to the bearing 9, which rotatably supports the circular landside 10. An arm 11 65 rigidly secured to the bearing 9 is bent to extend around the landward face of the landside 10 to form a scraper 12; a scraper 13 for the periphery of the rolling landside 70 10 is bolted to the bend of the arm 11. The bearing 9 is mounted on the bracket 8 to position the rotatable landside 10 so that it is declined toward the wall of the furrow and contacts therewith at the bottom of the furrow.

75 The bracket 8 is preferably made of steel plate, the body portion being provided with ribs or corrugations 14 and the edges being turned outwardly, as at 15, to stiffen the 80 member; the outwardly turned edges also forming flanges, best seen in Figure 4, to engage with and hold the bearing 9. The bracket is formed, as indicated at 16, to support the rotatable landside 10 laterally 85 in proper position with respect to the short landside portion of the plow body.

90 In order that any one of the rolling landside units, which are manufactured complete, separate from the plow body units, 95 will attach to any one of the body units and occupy its proper position relative to the plow body, without need for special fitting or adjustment, the forward portion of the bracket 8 is provided with a face that is positioned to correspond with the predetermined fixed position of the frog portion 4^a, 100 regard, of course, being given to the inclination at which the rolling landside is to stand relative to the furrow wall.

105 It is therefore apparent that to combine the two units for associated use, it is only necessary to secure the forward portion of the bracket 8 to the frog portion 4^a and the parts will be in their correct working rela- 110

tionship. My invention makes it possible to attach the rolling landside unit to the body unit with the same bolts that fasten the beam unit to the body unit, thereby simplifying and lessening the cost of the structure.

What I claim is—

1. In a plow, the combination of a beam and standard having a positioning surface at its landward side, a plow body, a frog for attaching the plow body to the standard and having a surface adapted to fit against and be secured to said positioning surface, a rolling landside, and a bracket supporting said landside and adapted to overlie and be secured to the landward side of the frog.
2. In a plow, the combination of a beam and standard having a positioning surface at its landward side conforming to a predetermined standard, a plow body, a frog for attaching the plow body to the standard and having a surface adapted to fit against and be secured to said positioning surface, a rolling landside, and a bracket supporting said landside and adapted to overlie and be secured to the landward side of the frog.
3. In a plow, the combination of a beam and standard having a positioning surface, a plow body, a frog for attaching the plow body to the standard and having a surface adapted to fit against and be secured to said positioning surface, a rolling landside, a bracket supporting said landside adapted to overlie and be secured to that portion of the frog that is secured to the standard, and securing means common to the standard, the frog, and the bracket, for securing said parts together.
4. In a plow, the combination of a beam and standard having a positioning surface at its landward side, a plow body, a frog for attaching the plow body to the standard and having its surface adapted to fit against and be secured to the positioning surface of the standard, a bracket supported solely by the standard, the front end of said bracket being adapted to overlie and be secured to the landward side of the frog, and a rolling landside journaled on the rear end portion of said bracket.

5. In a plow, the combination with a plow unit comprising a beam and standard, a plow body, and a frog secured to the plow body and to the standard, of a rolling landside, and a bracket supporting said landside and secured to the frog that portion of the frog that is secured to the standard being disposed between the bracket and the standard, whereby the standard and frog may be arranged to provide an attaching surface for the bracket positioned to conform to a predetermined standard.

6. In a plow, the combination with a plow comprising a beam and standard, a plow body, and a frog secured to the plow body and to the standard, of a bracket secured to the standard over a portion of the frog and extending rearwardly therefrom, said bracket being bent inwardly at a point back of the standard and having corrugations at its bent portion for supporting its rear portion against deflection, and a rolling landside journaled on the rear end portion of said bracket.

7. In a plow, the combination with a plow comprising a beam and standard, a plow body, and a frog secured to the plow body and to the standard, of a bracket secured at its forward end to the standard over the frog and extending rearwardly therefrom, the rear end portion of said bracket being unsupported and being offset toward the furrow side of the plow, and a rolling landside journaled on the rear end portion of said bracket.

8. In a plow, the combination of a beam and standard, a plow body having a frog secured to the standard at the landward side thereof, a rotary landside, and a support for the rotary landside overlying and secured to the landward side of the frog.

9. In a plow, the combination of a beam and standard, a plow body having a frog secured to the standard at the landward side thereof, a rotary landside, a support for the rotary landside secured to the landward side of the frog, and securing means for said support common to said frog and standard.

THEOPHILUS BROWN.
